Julius Weis,
by: Howard Fisch,
Attorney.

UNITED STATES PATENT OFFICE.

JULIUS WEIS, OF ST. PAUL, MINNESOTA.

SAFETY-PIN.

1,313,846.

Specification of Letters Patent. Patented Aug. 19, 1919.

Application filed August 19, 1918. Serial No. 250,614.

To all whom it may concern:

Be it known that I, JULIUS WEIS, a citizen of the United States, residing at St. Paul, in the county of Ramsey and State of Minnesota, have invented a new and useful Improvement in Safety-Pins, of which the following is a specification.

My invention relates to a safety-pin which is easily formed, having a simple construction, and formed of any suitable material, being adapted for use on a simple safety-pin or pins, brooches or other articles of a similar nature.

The primary object of my device is in a safety-pin with locking means to prevent horizontal movement of the pin arm when the pointed end of the same is held in the sheath or guard and to prevent its accidental opening when in use.

A further object of the invention is in means for locking the pin arm against longitudinal movement in either direction, to prevent its being drawn out of the sheath which covers the sharp pointed end of the pin arm when the safety-pin is closed. This construction allows considerable strain to be exerted on the pin arm, when the safety-pin is in use, and closed, without any danger of the arm becoming disengaged from the protecting sheath.

It is also an object of my safety-pin to form means on the body portion or loop of the safety-pin which is adapted to hold the pin flat with the outer surface of the garment to which it is attached.

In the drawing forming part of this specification:

Figure 1 is a perspective view of my safety-pin as it would appear when attached to a garment, only a portion of the garment being illustrated.

Fig. 2 is a perspective view of the safety-pin in open position.

Fig. 3 is a perspective view of an alternative form of my safety-pin.

Fig. 4 is a cross section on the line 4—4 of Fig. 3, illustrating a portion of a garment, and in dotted outline the position of the pin arm when released from the point holding sheath.

Fig. 5 is an end elevation looking at the safety-pin from the sheath end.

Fig. 6 is a cross section on the line 6—6 of Fig. 7 also illustrating in dotted outline a portion of the connecting parts.

Fig. 7 is a front elevation of the safety-pin illustrating the same in closed position.

Figs. 8 and 9 are details of a portion of the safety-pin illustrating an alternative construction.

Fig. 10 is a perspective view of a brooch illustrating the back of the same, which is equipped with my safety-pin.

In the drawing A represents my safety-pin which is formed from a single piece of spring wire 2 such as brass or other suitable material, the wire 2 being bent to form a loop or body portion 3 which is substantially rectangular in shape. One end of the wire 2 forms the pin arm 4 which is formed with a free end 5, and which is adapted to open or close the loop portion 3, the arm 4 forming one of the longitudinal sides of the loop 2.

The other end of the wire 2 is bent to form loops or recesses 6 and 7 which are connected by a longitudinally extending shank portion 8, the wire 2 being bent upward from the recess or loop 7 and then curved downward, forming a loop 9 and positioning the end 10 adjacent to the shank 8 and the recess 6.

The loops 6 and 7 with the connecting shank 8 and the loop 9 form a sheath or guard B for the free end 5 of the arm 4 and when it is desired to close the pin A the free end 5 is inserted in the recess or loop 6, pressing the end or catch 10 out of the path of the free end 5, and allowing it to enter the recess 6. The end 10 of the wire 2 will automatically spring back adjacent to the shank 8 and directly above the free end of the arm 4 to engage the same and form a stop or catch to prevent the free end 5 from being accidentally disengaged from the sheath B, the apex 11 of the end 5 is adapted to extend a short distance into the recess 7 when the arm 4 is in closed position, and as illustrated in Fig. 6. The recess 7 forms a guard for the sharp point 11 of the free end 5.

A recess 12 is formed on one side of the arm 4 near the point 11, so as to engage the rear side 13 of the recess 6 and the front side 14 of the recess 6, engaging the front surface of the arm 4 to force the recess 12 into engagement with the portion 13, when the arm 4 is inserted or snapped into position in the sheath B, to close the pin A. When the recess 12 is engaged by the por-

tion 13 it is locked to rigidly hold the arm 4 against forward or backward longitudinal movement, to prevent the free end 5 from becoming disengaged from the sheath 5 B when the pin A is closed, even when a severe strain or load is carried by the arm 4.

The long side 15 of the loop 2, which is opposite to the arm 4, is bent inwardly to 10 form an offset or recess portion 16 which extends longitudinally of the portion 15 approximately the full length of the same and which is adapted to receive the folds C of a garment when the pin A is secured to the 15 same, leaving the arm 4 free to carry another portion of the garment or other material, and preventing the pin A from becoming easily disengaged from the garment B when the pin A is open. The pin A will 20 lie flush with the surface of the garment to which it is attached when the folds C are held in the recess 16.

In the construction illustrated in Figs. 3 and 4 the wire 2 is bent so as to form projecting members 17 on either end of the recess portion 16. The members 17 tend to form stops which engage the surface of the garment when the folds are held in the recess 16 to prevent the easy rotation of the 30 safety-pin A about the recess portion 16, also holding the pin A flat against the garment at all times.

The arm 4 is connected to the portion 15 by a short shank 18 and the pin A is bent 35 so that the free end 5 of the arm 4 will rotate horizontally from the shank 18 when the arm 4 is released from the sheath 3, and as indicated by the arrows in Fig. 2. Thus when the arm 4 is released from the sheath 40 B instead of moving transversely away from the pin A it will move horizontally, rotating with the shank 18 as its axis, assuming the position illustrated in Fig. 2 and in dotted lines in Fig. 4.

45 The end 10 forms a catch to hold the free end 5 in the sheath B and the free end 5 can only be released from the sheath B by pressing the end 10 of the loop 9 backward into the position illustrated in dotted outline in 50 Fig. 5, thus moving the end 10 out of the path of the arm 4 and allowing it to be disengaged from the sheath by moving it upward to disengage it from the recess 6.

The arm 4 can be formed with recesses 19 55 on either side of the same, and the portions 13 and 14 positioned close enough together so as to engage in the recess 19 when the free end 5 of the arm 4 is inserted in the sheath B, as illustrated in Figs. 8 and 9. 60 This alternative construction of the arm 4 illustrates another manner in which the arm 4 is locked in the recess 6 to hold it against longitudinal backward movement and accidental disengagement from the sheath.

65 In use of a safety-pin, the pin arm very

often becomes bent from carrying a heavy strain, and thus causes the pointed end, which is held in the sheath, to become disengaged from the same, thereby opening the pin and instead of being a safety-pin, it is 70 a dangerous device. With my construction of safety-pin A, I desire to prevent the arm 4 from moving longitudinally forward or backward by the locking means which is formed by the recess 12 of the engaging 75 portions 13 and 14, thus holding the arm 4 locked against longitudinal movement in either direction, and allowing the use of a skeleton or open formed sheath, such as B, which is provided with a locking means to 80 prevent transverse movement of the pointed end of the arm 4 when it is held in the sheath B. In this manner the arm 4 of the pin A is held against longitudinal or transverse movement by the locking means in the 85 sheath B, making it practically impossible to accidentally unlock the same.

The locking means formed in the sheath portion of the safety-pin by the members 90 13 and 14, together with the notch 12 hold the pin arm 4 against longitudinal movement in either direction, thus preventing the sharp point 11 of the pin arm 4 from moving forward in the recess 7, which would project the same from the sheath B where 95 it might be apt to stick or injure the user of the safety-pin. The spring arm or end 10 of the loop 9 forms a spring catch to hold the free end 5 of the pin arm 4 from moving in the opposite or transverse direction 100 of the pin, thereby holding the free end of the pin arm securely locked against movement in any direction in the sheath B. To release the free end 5 of the arm 4 it is necessary to press the spring catch 10 into 105 open position, as illustrated in dotted lines in Fig. 5, whereupon the free end 5 can be lifted out of the recess 6, disengaging it from the projecting sheath.

Fig. 10 illustrates the pin arm 4 hinged 110 in the ordinary manner to the back of a brooch E, and the recess 20, which is formed near the free end 5, is adapted to be engaged by the spring clasp 21, while the sharp pointed end 11 is positioned in the 115 guard 22 when the pin arm 4 is in closed position. The recess 20 is similar in function to the recesses 12 and 19 of the constructions illustrated. The recess 20 is firmly engaged by the spring clasp 21 to 120 hold the pin 4 against longitudinal and transverse movement in either direction, thus making a very desirable construction for a brooch, and preventing the easy bending of the arm, which would cause it to become disengaged from the sheath in the ordinary construction of safety-pins where the pin is not held against longitudinal movement on its free pointed end.

In accordance with the patent statutes, I 130

have described the principles of operation of my invention, together with the apparatus which I now consider to represent the best embodiment thereof, but I desire to 5
5 have it understood that the construction is only illustrative, and that the invention can be carried out by other means and applied to uses other than those above set forth within the scope of the following
10 claims.

Having described my invention what I claim is:

1. In a safety-pin, having a body portion, a sheath for the pin point of the pin arm, 15 means for connecting the pin arm with the body portion of said safety-pin so that folds of a garment or other material may be passed freely from the pin point of said arm to the body portion and means for holding 20 said pin point in said sheath against transverse or longitudinal movement.

2. In a safety-pin having means for locking the free pointed end of the pin arm in a sheath against longitudinal and transverse 25 movement and means in the shank connecting said pin arm with the body portion of said safety-pin for causing the free end of said pin arm to rotate with said shank as its axis when released from the sheath.

3. In a safety-pin formed from a single 30 piece of material, having a sheath for the pointed end of the pin arm, resilient locking means formed in said sheath for holding the pointed end of said arm against transverse or disengaging movement in said 35 sheath, whereby said pointed end is held in said sheath to prevent it from accidentally disengaging from said sheath.

4. In a safety-pin formed from a piece 40 of wire, a sheath on one end of said pin, an offset holding loop formed in the body portion of said pin extending in a transverse plane to said body portion, an arm for closing said body portion, a pointed end formed 45 on the free end of said arm, and means formed in said sheath and arm for locking said pointed end in said sheath against transverse and longitudinal movement.

5. In a safety-pin formed from a piece of 50 wire, a sheath or guard on one end, a holding loop forming the body portion of said pin, a pin arm for closing said loop and

forming one of the sides thereof, a smooth shank connecting said pin arm with the other side of said loop which forms the body 55 portion of said pin and means for automatically locking the pointed end of said arm in said sheath against transverse and longitudinal movement, said smooth shank allowing the folds of a garment to be passed 60 from the pin arm to the holding loop or body portion of said pin for the purposes specified.

6. In a safety-pin, having a substantially rectangular body portion, an offset portion 65 formed in one of the long sides of said loop for receiving the folds of a garment to which said pin is adapted to be attached, means projecting from said offset portion for preventing the rotation of said pin 70 about the offset portion, a sheath or guard formed on said pin, a pin arm forming one side of said loop, the free end of which is adapted to be held in said sheath, and a spring shoulder formed in said sheath for 75 engaging said arm to hold it in said holding recess and preventing accidental or horizontal movement of the free end of said arm, to prevent said arm from accidentally becoming disengaged from said sheath. 80

7. In a safety-pin of the class described, having a pin arm, guard means for holding the free end of said pin arm, and a spring arm in said guard the end of which is adapted to engage the free end of said pin 85 arm to prevent said free end of said arm from moving in a transverse direction, or from accidentally becoming disengaged from said guard.

8. In a safety-pin of the class described 90 having a pin arm, a sheath for the pointed end of said pin arm, means for connecting said pin arm with the body portion of said safety-pin which causes the free end of said pin arm to rotate in a horizontal direction 95 with said connecting means as its axis when the free end of said pin arm is released from said sheath and a spring arm in said sheath the end of which is adapted to engage the free end of said pin arm to hold 100 the same against accidental disengagement from said sheath.

JULIUS WEIS.
